UNITED STATES PATENT OFFICE.

JOHN G. W. GRIEVES AND CHARLES S. GRIEVES, OF AMESBURY,
MASSACHUSETTS.

CARPENTER'S BRACKET.

SPECIFICATION forming part of Letters Patent No. 788,899, dated May 2, 1905.

Application filed January 28, 1905. Serial No. 243,093.

To all whom it may concern:

Be it known that we, JOHN G. W. GRIEVES and CHARLES S. GRIEVES, citizens of the United States, residing in Amesbury, in the 5 county of Essex and State of Massachusetts, have invented certain new and useful Improvements in Carpenters' Brackets, of which the following is a specification.

This invention relates to carpenters' brackets adapted to be applied to the outside wall of a building for supporting a plank, stage, or other article or structure on which the carpenter or other workman may stand while at work on the building.

15 The invention has for its particular object to provide a construction whereby the bracket may be applied to the outer wall of a building without interfering with, marring, or puncturing the plastering or lathing on the inner wall.

20 The nature of the invention is fully described below and illustrated in the accompanying drawings, in which—

Figure 1 is a transverse vertical section of a portion of a building-wall, including the outer 25 wall, the stud, the laths, and the plaster, said wall being prepared for the application of our improved bracket, and a view in side elevation of our improved bracket in position for being applied to the wall. Fig. 2 is an enlarged ver-

30 tical section taken through the wall and a portion of the bracket, the bracket being illustrated as locked in position. Fig. 3 is a plan view of the inner end of the locking mechanism removed.

35 Similar letters of reference indicate corresponding parts.

a represents the horizontal or supporting portion of the bracket, *b* the upright portion, which rests against the wall, and *c* the base.

40 *d* and *e* are respectively the outer and inner walls of a building, the outer wall *d* being provided with a horizontal hole *f*, whereby our bracket may be applied.

g represents a socket or tubular case preferably closed at its front end by a plug or equivalent device *h* and open at its rear end. One of the side walls of this case is provided with a horizontal slot *k*, from which a slot *l* extends at right angles down to the bottom

of the case, said slot being such as is used in 50 an ordinary lantern-joint. A bolt *n* lies in this tubular case or socket, and a short arm *p* extends radially from said bolt through the right-angled slot *k* and is provided on its outer end with a suitable handle or ball *r*. 55 From the inner end of this tube or socket there extends horizontally two parallel ears *s*, whose planes are on vertical lines, and the inner end *n'* of the bolt is flat and on a vertical plane. 60

t represents a latch pivotally secured at *u* to and between the ears *s*, the upper or inner end *t'* of said latch being flat and at right angles with its sides and the outer end *t''* being preferably rounded off or curved, as 65 shown. The tube or case *g* is supported against the under side of the part *a* of the bracket by means of one or more bolts *v*, which extend through said part *a* and suitable holes *w*, formed in the case *g* and plug *h*, and 70 are provided with suitable nuts *w'*, and the case, furthermore, extends through a horizontal hole in the upright portion *b*. By this means it is held firmly in a horizontal position and may be adjusted horizontally as 75 desired.

In operation when it is desired to securely and rigidly apply the bracket to the wall a hole *f* is first made in the outer wall, said hole being in such a position as to be accessible from a window, ladder, or other structure. The carpenter places the bracket with the parts in the position indicated in Fig. 1— 80 that is, with the arm *p* swung down through the slot *l* and with the latch *t* in a horizontal position and held therein by the outer flat end *n'* of the bolt *n*, which rests against the flat end *t'* of the latch *t*. The bracket is then placed opposite the hole *f* and moved toward the building and the latch inserted in the hole, 85 the inner end of the tube extending for a sufficient distance beyond the upright portion *b* of the bracket to reach entirely through the hole *f* and the length of the latch *t* being less than the width of the space between the outer 90 and inner walls *d e*. In theory the carpenter should then reach down and swing the arm *p* up from the slot *l* into the slot *k*, thus allow-

95

ing the latch *t* to drop; but in practice the ordinary jar produced by placing the bracket in position against the wall is such that the arm *p* is loosened and swings up from the slot *l* into 5 the slot *k* by reason of the weight of the latch *t*, which swings down and forces slightly back the bolt *n*. The carpenter, therefore, in practice reaches for the bolt *p*, which he finds disengaged from the slot *l*, and pushes it down 10 into the vertical position shown in Fig. 2 in said slot *l*. Thus the latch is locked in the position indicated in Fig. 2 against the inner surface of the outer wall, being held in such locked position by the outer end *n'* of the bolt 15 *n*, which bears against the rear portion of the flat bottom of the latch *t*.

As will be readily seen from the above description, the workman needs but one hand with which to adjust the locking device, so 20 that his other hand is free to hold himself safely in position, as in a window, for example.

In practice we may slightly vary the height of the lantern-joint, more particularly the 25 slot *k*, making it as near the extreme bottom of the tubular case as practicable.

The curved end of the latch facilitates its entrance into the hole *f*.

Having thus fully described our invention, 30 what we claim, and desire to secure by Letters Patent, is—

1. In a device of the character described, a bracket; a tubular case or socket supported substantially horizontally by the bracket; a 35 bolt adapted to slide in said tubular case; a

latch pivotally secured to the outer end of the tubular case, the adjacent ends of the bolt and latch being substantially parallel when the latch is in horizontal line with the bolt, and means for locking the bolt with its 40 end against either the end or bottom of the latch, for the purpose set forth.

2. In a device of the character described, a bracket; the tubular case or socket *g* secured substantially horizontally to the bracket; the 45 bolt *n* sliding in said tubular case and provided with the squared end *n'*; the latch *t* pivotally secured to the end of the tubular case and having the squared end *f'*; and means for sliding the bolt in the case and lock- 50 ing it thereto, for the purpose set forth.

3. In a device of the character described, a bracket; the tubular case or socket *g* provided with the lantern-joint slots *k*, *l*, and secured to the bracket with its outer end projecting beyond the back of the bracket; the bolt *n* sliding in said bracket; the arm *p* extending from the bolt through said slots; and the latch *f* hinged to the end of the bolt, and adapted to be held in line therewith or at right 55 angles thereto by sliding the bolt in opposite directions, for the purpose set forth.

In testimony whereof we have signed our names to this specification in the presence of two subscribing witnesses.

JOHN G. W. GRIEVES.
CHARLES S. GRIEVES.
